UNITED STATES PATENT OFFICE.

HERMAN PARPERT, EDWARD BOEKENKAMP, AND LOUIS STOCKSTROM, OF ST. LOUIS, MISSOURI, ASSIGNORS TO AMERICAN STOVE COMPANY, OF ST. LOUIS, MISSOURI, A CORPORATION OF NEW JERSEY.

GASOLENE-BURNER.

1,258,039.

Specification of Letters Patent.

Patented Mar. 5, 1918.

Application filed November 6, 1914. Serial No. 870,626.

To all whom it may concern:

Be it known that we, HERMAN PARPERT, EDWARD BOEKENKAMP, and LOUIS STOCKSTROM, citizens of the United States, residing at St. Louis, State of Missouri, have invented certain new and useful Improvements in Gasolene-Burners, of which the following is a specification, reference being had therein to the accompanying drawing.

10 Our invention relates to improvements in gasolene burners, and pertains to that type of burner in which the gasolene is vaporized or evaporated in the presence of air and passes downwardly through a tube to the lower end of the burner.

The object of our invention is to provide means whereby the burner may be quickly started in cold weather with heavy gasolene and in order to accomplish this, we place 20 an auxiliary torch or burner under the hot air flue for heating the air in starting the evaporation of the gasolene.

Another object of our invention is to provide a burner of this character in which a 25 specially designed hood and sub-burner are used and having certain details of structure and operation, hereinafter more fully set forth.

It is well known to those skilled in the 30 art that for several years past the gasolene furnished to the public has gradually become heavier and more difficult to thoroughly and rapidly evaporate in the presence of air, and for this reason the heavy 35 grade of gasolene furnished to the public has not been efficiently evaporated, taken care of and thoroughly mixed with the air in the construction of evaporator used in this type of stoves with the lighter grades 40 of gasolene which were furnished to the public at the time this class of stove was first successfully placed upon the market.

Referring now to the drawings:

Figure 1 is an enlarged side elevation of 45 a gasolene burner of the type to which our invention relates, the burner and the evaporating tube being shown partly in vertical section.

Fig. 2 is a detached perspective view of 50 the sub-burner and cap therefor.

Fig. 3 is a top plan view of Fig. 1, showing the air and gas evaporator tube broken away.

Fig. 4 is a perspective view of the auxil-

iary torch for starting the burner in operation.

Fig. 5 is a vertical sectional view.

Fig. 6 is a transverse sectional view of the gasolene burner showing a modified form of feeding heated air to the vaporizer.

Referring now to the drawings, 1 is the burner of the type well-known in the art with the exception of a slight modification of the burner cap and sub-burner, which we will proceed to describe. This burner 65 consists of the cylindrical body portion 2, having a cylindrical, vertical central tube 3 therein, said tube having its upper end reduced, as indicated at 3'. Resting upon the upper end of the tube 3 is a cap 4, which 70 has a central downwardly disposed cylindrical portion 4, resting upon the upper reduced end of the tube 3. Supported by the upper end of the tube 3 and spaced from the cap 4, is what is known as the burner 75 cap 5, of the form clearly shown in Fig. 1 of the drawings. The lower end of the tube 3, is provided with a sub-burner 6, having the openings 7 therein, and a central opening through which extends a short tube 8, 80 which also passes downwardly through a central hole in the bottom 9 of the body 2, and by means of which the central tube 3 is supplied with air to support combustion, as is clearly shown in Fig. 1 of the drawing. The vertical tube 3, adjacent its upper 85 end, is provided with an outwardly extending circular flange 9', communicating with an opening 10 in the tube 3. Fitting within the flange 9' and communicating with an 90 opening 10 is a short tube 11, which extends outwardly through the body 2 and a slight distance beyond the same.

An air intake tube 12 is arranged in a horizontal position and has its ends terminating at one side adjacent the burner tube as shown in Fig. 3 of the drawing. The end of the tube 12 is open to allow air to pass thereto. The tube 12 is bent upwardly, as indicated at 13, and then outwardly, as indicated at 14, and communicates with an evaporating chamber 15. This chamber 15 is provided with a vertically disposed elongated evaporating tube 16 arranged therein and spaced from the walls 105 thereof, as clearly shown in Fig. 1 of the drawing.

The upper end of the chamber 15 directly

over the evaporating tube 16 is provided with an oil supply 16' which is adapted to discharge directly upon the upper end of the evaporating tube. The evaporator 15 has its lower end contracted, as indicated at 5 17, and into which fits the upper end 18 of the vapor tube 19. The perforated evaporator tube 16 fits within the upper end of the upwardly turned end 18 of the vapor tube 10 and owing to the contracted end 17 of the evaporator chamber 15 it will be seen that the evaporator tube is spaced from the evaporator chamber throughout its entire 15 length. The lower end of the vapor tube 19 communicates with the lower end of the burner tube 2, for supplying the burner with vapor, as is well understood by those skilled in the art.

The air tube 12, as clearly shown in Fig. 20 3, of the drawing, is at one side of the burner tube 2 and has connected thereto a downwardly curved tube 20, which surrounds the extension of the tube 11 on the outside of the burner tube 2, and has its 25 ends spaced a slight distance from the burner to allow a certain amount of fresh air to be drawn inwardly as the hot air passes from the tube 11.

Below the tube 12 is arranged an inverted 30 V-shaped housing 21, which has its upper end open, as indicated at 22, and at its ends the upwardly and outwardly extending ears 23 and 24, which are secured to the lower face of the tube 12, directly below the same. 35 This housing 21 has its lower end open and has placed therein a plate 25, which has its ends a short distance from the side walls thereof. Supported by the plate 25 are the obliquely arranged perforated plates 26, extending parallel with the side walls of the housing and spaced therefrom, said plates terminating in a vertical line with the opening in the upper end of the housing. One end 27 of the housing is provided with an 40 opening 28, through which the torch 29 passes and is adapted to burn within the housing between the perforated plates 26 and the plate 25. The torch, as shown, is of a cylindrical form having its outer end 45 perforated, as indicated at 30, and its outer and its opposite end is provided with a handle 31 whereby the torch may be readily handled. The end of the torch adjacent the perforations 30 is filled with an absorbent 50 asbestos which absorbs oil but allows it to freely burn through the opening as is readily understood. The torch may be dipped into a can of oil, but we prefer to provide the oil tank of our stove to which the burner is 55 applied, with a specially constructed tube on a level with the float valve, whereby the torch is at all times in place and thoroughly saturated so that it is ready for use.

In operation the torch is inserted through 60 the opening 28 within the housing 21 and

lighted. The air passes upwardly between the side walls 21 of the housing and through the perforated plates 26 to the burner and is heated and passes upwardly through the slot 22 directly against the lower face of the tube 12. This heats the tube 12, thus 70 causing more rapid evaporation of the gasoline as is readily understood. The torch holds sufficient gasoline or other liquid fuel to thoroughly heat the tube 12 to start the 75 burner. After the burner is started, it will be readily understood that the tube 12 is sufficiently close to the burner to be heated, and the air passing in the open end thereof is likewise heated. 80

While we have shown and described this specific form of auxiliary heater, it will be understood that this could be varied without departing from our invention.

Having thus described our invention, what 85 we claim and desire to secure by Letters Patent is:

1. A heater for gasoline burners comprising an elongated housing having an open lower end and a contracted upper end, a 90 tubular torch having a handle at one end and adapted to be inserted in the housing and means carried by the upper end of the housing for supporting the burner below the center of the air supply pipe of the evaporator of a burner.

2. A heater for gasoline burners, comprising an inverted V-shaped housing having an open lower end, a plate extending across the lower end of the housing and having 100 obliquely arranged perforated walls extending parallel to the walls of the housing and spaced therefrom, the upper end of the housing having an elongated slot extending across the face thereof, one end of the housing having an opening, a tubular torch supported within the opening, and means carried by the upper end of the housing for supporting the same below the center of the air tube leading to the evaporator of a 110 burner.

3. A heater for gasoline burners, comprising an inverted V-shaped housing having an open lower end, a plate extending across the lower end of the housing and having 115 obliquely perforated walls extending parallel with the walls of the housing and spaced therefrom, the upper end of the housing having an elongated slot extending across the face thereof, one end of the housing having an opening, a tubular torch passing through the opening in the housing and laterally extending ears carried by the upper end of the housing and adapted to be secured to the lower face of the air-supply 120 tube of the evaporator of a burner.

4. A heater for gasoline burners comprising an inverted V-shaped housing having an open lower end, a plate extending across the lower end of the housing and having 130

obliquely arranged perforated walls extending parallel with the walls of the housing and spaced therefrom, the upper end of the housing having an elongated slot extending 5 across the face thereof, the end of the housing having an opening, a tubular torch removably supported within the opening and having a handle at its outer end for removing the same from the housing, and laterally extending ears carried by the ends of 10 the housing and adapted to be fastened to the lower face of the air tube of the evaporator of a burner.

5. A heater for gasoline burners comprising an inverted V-shaped housing having an open lower end, a plate extending across the lower end of the housing and having obliquely arranged perforated falls extending parallel with the walls of the housing 15 and spaced therefrom, the upper end of the 20

housing having an elongated slot extending across the face thereof, the end of the housing having an opening, a tubular torch removably supported within the opening and having a handle at its outer end for removing the same from the housing and also serving as a plug for the torch and means carried by the ends of the housing for securing the same to the lower face of the air tube of the evaporator of a burner. 25

In testimony whereof we hereunto affix our signatures in the presence of two witnesses.

HERMAN PARPERT.
